UNITED STATES PATENT OFFICE.

ARTHUR CYRIL HUTT, OF WALLINGTON, ENGLAND.

SOOT-CLEANING APPLIANCE FOR BOILERS.

1,315,839.

Specification of Letters Patent.

Patented Sept. 9, 1919.

Application filed March 25, 1919. Serial No. 284,992.

To all whom it may concern:

Be it known that I, ARTHUR CYRIL HUTT, a subject of the King of the United Kingdom of Great Britain and Ireland, and residing 5 at Wallington, Surrey, England, have invented a certain new and useful Improvement in Soot-Cleaning Appliances for Boilers, of which the following is a specification.

This invention relates to soot cleaning appliances for boilers whether of the marine or 10 of the land type.

As a means of disposing of the soot, according to the invention there is utilized the suction of an ejector; where an ash ejector 15 is fitted, as in ships, suction therefrom may be utilized to discharge the soot overboard.

A practical application according to this invention includes a system of pipes and permanent fittings on the soot casings, flues, 20 smoke boxes and uptakes of boilers, whereby the soot may readily be removed by suction, whether or not the boiler is steaming.

For marine boilers the vacuum may be obtained from the usual ash ejector, in which 25 event the soot is discharged overboard through the usual ash ejector pipes.

In the accompanying drawings Figure 1 is a plan illustrating diagrammatically a 30 battery of boilers equipped with soot-cleaning apparatus according to the invention. Figs. 2, 3, 4 and 5 illustrate details. Figs. 6 and 7 show alternative arrangements.

As shown, a main soot suction pipe 1 leading 35 from the ash ejector 2 extends between the backs of the boilers. Near the ash ejector 2 are fitted a shut-off valve 3' and a flap check valve 3; the flap valve allows for the escape of water, so that the pipe 1 and soot casings cannot be flooded in the event of a 40 heavy sea coming down the overboard discharge pipe when the soot cleaning apparatus is in use and the valve 3' is open.

In the main pipe 1, behind the boilers, are fitted valve boxes 4 which are fitted with 45 valves (operable by spindles 4' from the front of the boilers) from which main pipe 1 branch-pipes 5 are led through the back soot casing, through the soot casing 6, to the outside of the front soot casing, there being 50 fitted at the end of each pipe a cap having a testing orifice 6', which also allows a small quantity of air to pass through the pipe and keep it cool when not in use.

The pipe section within each casing is 55 formed with perforations 7 at intervals. Fitted in each soot casing is a sliding rod or

pipe 8 fitted with scrapers 9 and having a handle 10 at the front of the boiler whereby the soot is moved to and fro past the perforations 7 and so sucked out; the scrapers 60 also serving the purpose of keeping the perforations clear in the event of clinker blocking the same. The scrapers may be fitted to a solid operating rod, or a tubular rod to allow a small quantity of air to pass through 65 to keep it cool.

Alternatively, the suction pipe formed with perforations may slide in the casing, as shown in Fig. 5. The suction pipe 5^a slides in the soot casing and valve box 4 and when 70 it is pushed back to the valve seating 13 suction is shut off the sliding tube; when it is pulled forward, the sliding tube is open to the main suction pipe 5. Scrapers 12 are 75 fitted in the soot casing for the purpose of keeping the perforations clear in the event of clinker blocking the same.

Fittings may be provided on the main pipe 1 and valve boxes 4 for cleaning the uptakes, tubes and other parts of the boiler; 80 these fittings having connections 11 for taking flexible hose provided with suitable nozzles for clearing.

Fig. 7 shows an arrangement as fitted to a Lancashire boiler. Suction tubes 5^b are 85 situated in the flues 6^a from front to back of the boilers. The main pipe 1 may run along the front or back of the boilers as most convenient. Scrapers 9^a are provided for 90 each suction tube.

Fig. 6 shows an arrangement as fitted to a Scotch boiler, (return tube boiler). Suction tubes are situated in the bottom of the smoke box casings 6^b and are connected by branch pipes 5^c to the main suction pipe 1 95 running below the floorplates. Each suction pipe has a corresponding scraper 9.

In this specification the term soot is intended to comprise fine ash, clinker and all fine dust and solid matter carried by draft 100 from the fire toward the chimney or furnace.

What I claim is:-

1. A soot cleaning apparatus for boilers comprising the combination with a suction 105 pipe, ash ejector and soot casings for the boilers, of perforated pipes mounted in said soot casings, and external scrapers for keeping said perforations open, said perforated pipes and scrapers being relatively movable, and a piping system connecting said perforated pipes with said ejector. 110

2. A soot cleaning apparatus for boilers comprising the combination with a suction ash ejector and soot casings for the boilers, of perforated pipes mounted in said soot casings, external scrapers encircling said pipes, sliding rods to which said scrapers are fitted and which rods are provided with operating handles, and a piping system connecting said perforated pipes with said 10 ejector.
3. A soot cleaning apparatus for boilers comprising the combination with a suction ash ejector and soot casings for the boilers, of perforated pipes mounted in said soot casings and external scrapers for keeping 15

said perforations open, said perforated pipes and scrapers being relatively movable, and a piping system connecting said perforated pipes with said ejector, said piping system having a shut-off valve and a flap or 20 check valve which will prevent said piping system from being flooded when said shut-off valve is open.

In testimony whereof I have signed my name to this specification in the presence of 25 two subscribing witnesses.

ARTHUR CYRIL HUTT.
